UNITED STATES PATENT OFFICE.

WILLIAM T. HUNTER AND FLOYD R. HUNTER, OF ANN ARBOR, MICHIGAN.

DESIGN FOR A CLOCK.

50,106.

Specification for Design.

Patented Dec. 26, 1916.

Application filed June 7, 1916. Serial No. 102,343. Term of patent 7 years.

To all whom it may concern:

Be it known that we, WILLIAM T. HUNTER and FLOYD R. HUNTER, citizens of the United States, residing at Ann Arbor, in the county of Washtenaw and State of Michigan, have invented a new, original, and ornamental Design for Clocks, of which the following is a specification, reference being had to the accompanying drawing, forming part thereof.

The figure is a perspective view of a clock showing our new design.

We claim:

The ornamental design for a clock as shown.

WILLIAM T. HUNTER.
FLOYD R. HUNTER.

Witnesses:

L. C. BURNS,
D. W. SAWYER.
